UNITED STATES PATENT OFFICE.

ROY H. HATFIELD, OF LEWISTON, IDAHO, ASSIGNOR OF ONE-HALF TO CHARLES H. MURRAY, OF LEWISTON, IDAHO.

TIRE AND RIM TOOL.

Application filed June 16, 1926. Serial No. 116,430.

This invention relates to an improved automobile tire and rim tool and it has reference to an article of this kind which is especially, but not necessarily, adapted for the removing of the usual split band or ring which is used in association with disk wheels.

Briefly, the tool is composed of two parts; the first of which is in the form of a lever 10 adapted to be operated by the person doing the work, this lever being constructed to engage and separate the split ends of the removable band; together with an adjustable anchoring device for maintaining the lever 15 in operating position.

My principal aim is to provide an exceptionally simple and inexpensive tool of this class, which is highly practical, compact and convenient, and thoroughly reliable under 20 all conditions.

Other objects and advantages of the invention will become apparent from the following description and drawings.

In the accompanying drawings forming a 25 part of this application, and in which like numerals are employed to designate like parts throughout the same:

Figure 1 is a view in elevation and section showing the complete tool as it is used.

Fig. 2 is a view somewhat similar to Fig. 1, showing a further step in the operation 30 of the tool.

Fig. 3 is a detail view with portions broken away and shown in section to disclose the details more plainly.

Fig. 4 is a perspective view of one end of the bracing or anchoring arm.

Referring to the drawings in detail, the reference character 1 designates a tire, the 40 reference character 2 the disk wheel which is provided with the usual rim, the reference character 3 designates the movable slit band which is employed in connection with the rim and tire, 4 designates the enlarged central hub opening, and 5 the bolt holes which surround this opening.

The improved tool, comprises, as before stated, a lever 6 which is here shown as provided with a reduced portion 7 terminating 50 in a hook 8 which is adapted to engage the slit over-lapped end of the removable band 3. The anchoring device, which acts somewhat as a prop, is represented generally by the reference character 9 and this comprises

a screw 10 having a forked head 11 pivotally connected to the reduced lever end in 7 and threaded into a complementary part 12. A retaining nut 13 is employed for maintaining the parts in adjusted position.

It will be noticed particularly from Fig. 4, that the part 12 terminates in a downturned or curved end 14, adjacent which are outstanding stop pins 15. In practice, the downturned end 14 of the part 12 is inserted into one of the bolt holes 5 adjacent the main central opening 4 in the disk wheel. Then the screw 10 is properly adjusted to produce the desired leverage. Next, the hooked end 8 is engaged beneath the split ends of the expandable band 3 and these ends are 70 pryed apart and then back by swinging the lever as indicated in Fig. 2, the band is lifted off, thus facilitating removal of the tire.

The advantages, construction, and operation are plainly evident from the description and drawings, and a more lengthy description is thought unnecessary.

Minor changes coming within the field of invention claimed may be resorted to if desired.

Having thus described my invention, what I claim as new is:

1. A tire and rim tool of the class described comprising a lever having a reduced hooked end, and a bracing prop therefore, 85 said prop comprising a screw pivotally connected to the reduced end of the lever, a part into which said screw is threaded, a retaining nut in said screw cooperable with said part, said part terminating in a downturned end adapted to fit into a bolt hole in a disk wheel, and there being stop pins associated with said downturned end for resting against the disk.

2. A tire and rim tool of the class 95 described comprising a lever having a hooked end, and a bracing prop therefor, said prop comprising a pair of adjustably connected parts one of which is pivotally engaged with an intermediate portion of the lever and the other of which terminates in a laterally extending end adapted to fit into a bolt hole in a disk wheel, and there being stop pins associated with said laterally extending end for resting against the disk of 100 the disk wheel.

In testimony whereof I affix my signature.
ROY H. HATFIELD.
